UNITED STATES PATENT OFFICE

EDWIN R. JEROME, OF CRANSTON, RHODE ISLAND, ASSIGNOR TO VICTOR RING TRAVELER COMPANY, A CORPORATION OF RHODE ISLAND

RING TRAVELER

Application filed February 24, 1931. Serial No. 517,793.

This invention relates to a ring traveler of the type used in ring twisting or spinning, which operates about a horizontal flange of the ring; and has for its object to reduce the friction of the traveler on the ring thus reducing wear on both the traveler and the ring.

A further object of the invention is to produce a traveler which will cause an even tension on the yarn without strain on the yarn thus producing an evener yarn and one of improved quality.

A further object of the invention is the provision of a traveler which will permit of traverse motion of the yarn along the traveler to prevent the yarn from cutting the traveler in a single place.

A still further object of the invention is the provision of a balance between the traveler, the tension of the yarn extending there-through and centrifugal force so as to cause the traveler to substantially float around the ring with a minimum amount of friction upon the ring and with tipping and jamming of the traveler practically eliminated.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a side elevation partially diagrammatic, showing the ring traveler positioned about a bobbin with the yarn leading from the draft rolls thereto;

Fig. 2 is a perspective view of the traveler;

Figs. 3, 4 and 5 are sectional views showing the relative positions of the traveler and ring at different positions of the rail with respect to the bobbin, in which three positions different amounts of ballooning of the yarn take place.

In ring spinning and twisting of the type where a traveler is used to traverse a horizontal flange of the ring, the shank of the traveler has usually been on the arc of a circle and the traveler contacts with the ring at two or more points in its movement, commonly on the outside of the web and outside

of the flange of the ring thereby causing considerable friction or drag of the traveler on the ring and necessitating wear and heat which shortens the life of the traveler and detrimentally affects the ring, particularly at high speed operations. Further, the tension on the yarn is increased both between the traveler and the front draft roll and the traveler and the bobbin, but I have found that by so shaping and weighting the traveler as to balance the yarn tension against the centrifugal force the traveler substantially floats about the ring and is guided in its travel by but one point of contact with the ring thus causing the yarn to carry the weight of the traveler and cause less friction on the ring thus increasing the life of the traveler to a material extent, and I have found that one traveler design which will meet with these requirements has this single point of contact with the ring just above and adjacent to the inner horn of the traveler, whereby the traveler is guided by said contact with the inner edge of the ring and the yarn supports a large portion of the weight thereof and the friction is for practical purposes negligible; and the following is a detailed description of the present embodiment of this invention, illustrating the preferred means by which these advantageous results may be accomplished.

Travelers of the type herein described heretofore have been formed with horns connected by a substantially circular shank portion and variations in travelers have been made by varying the size of the circular shank. I have provided a traveler in which, with reference to the drawings, the horns 10 and 11 are straight and in substantially a single plane for a portion of their length and are connected by an elliptical shank 12 which is substantially the shape of the top of the flange 13 of the common ring 14.

Tension of the yarn exists between the front draft roll and the traveler (see Fig. 1) and between the traveler and the bobbin. As the traveler is moved rapidly about the ring centrifugal force tends to move the traveler radially outwardly of the ring and in order to compensate these two forces, I have pro-

vided a traveler so weighted as to balance these forces, and substantially float about the ring being guided by contact with but a single point thereon.

In operation about the ring, the centrifugal force causes the traveler to contact on the inner edge of the ring at point 15 located just above the horns 10 and 11, a substantial portion of the weight of the traveler from the point of contact 15 around to the horn 11 will be supported by the yarn 16 regardless of the various positions of the yarn 16 therealong and cause the traveler to float clear of the ring flange 13 except for this single point of contact 15, which point 15 is located in a horizontal plane passing through the center of the flange.

By this arrangement the traveler will run substantially vertically and the weight of the traveler itself will cause the tension on the yarn rather than friction of the traveler on the ring, an even tension is maintained on the yarn at all diameters of the bobbin between empty and full and at all positions of the ring rail and consequently more even and better yarn is obtained and more yards of the yarn of a given size may be produced.

The traveler is so shaped as to permit a traverse of the yarn along the shank thereof, three positions of which I have illustrated in Figures 3, 4 and 5 at either point 17, point 18 or point 19 along the shank. These different positions will be carried by the different relative positions of the yarn and traveler when the ring and rail are at the uppermost position of their travel the least ballooning will occur as in Figure 3, whereas when at the lowermost position of its travel greatest ballooning will occur as in Figure 5, while Figure 4 shows an intermediate position of the rail substantially at its middle position of its travel, as shown in Figure 1; thus, by providing a flat curvature substantially along the line of an ellipse, the yarn 16 will traverse along the shank portion of the traveler from the point 17 to the point 19, prevent the yarn from cutting the traveler at any one point, and thus abrading the yarn during operation. During this travel, the yarn runs clear of the ring at all times.

By the use of my improved traveler, I have increased the life of its operation several hundred per cent, with less wear on the ring and have provided a traveler which may be used with higher speed spindles, also making a better quality of yarn.

While I have described certain construction forms which embody the principles of my invention, it is obvious that other desired changes in arrangement may be made within the spirit and the scope of the invention as defined in the appended claims.

I claim:

1. A traveler for a horizontal ring flange

having horns extending beneath the ring flange, and a continuously curved shank portion connecting said horns shaped and weighted with respect to the pull of the yarn guided therethrough, and centrifugal force acting thereon so as to substantially float about the ring and be guided by contact with the ring at a single point only when in operation.

2. A traveler for a horizontal ring flange having horns extending beneath the ring flange, and a continuously curved shank portion connecting said horns shaped and weighted with respect to the pull of the yarn guided therethrough, and centrifugal force acting thereon so as to contact with the ring at the lower inside edge of the shank only when in operation.

3. A traveler for a horizontal ring flange having horns extending beneath the ring flange, and a continuously curved shank portion connecting said horns shaped and weighted with respect to the pull of the yarn guided therethrough, and centrifugal force acting thereon so as to contact with the ring at a single point above the horn when in operation.

4. A traveler for a horizontal ring flange having horns extending beneath the ring flange, and a continuously curved shank portion connecting said horns shaped and weighted with respect to the pull of the yarn guided therethrough, and centrifugal force acting thereon so as to contact with the ring at a single point only above the horn but adjacent thereto when in operation.

5. A traveler for a horizontal ring flange having horns extending beneath the ring flange, and a continuously curved shank portion connecting said horns to permit traverse of the yarn therealong in operation, said traveler contacting with the ring at the inner edge thereof above the horn and said yarn carrying the weight of the remainder of the traveler from the point of contact to the distant horn to prevent its contacting with the ring.

6. In combination a horizontal spinning ring, having a horizontally extending flange, a traveler for said ring having a continuously curved shank and embracing said flange and when running contacting therewith at a single point only on the inner surface of said flange, said point of contact being in a horizontal plane through the center of said flange.

7. In combination a horizontal spinning ring, having a horizontally extending flange, a traveler for said ring having a continuously curved shank and embracing said flange and when running contacting therewith at a single point only on the inner surface of said flange, said point of contact being in a horizontal plane through the center of said flange, said yarn running clear of the ring and supporting the traveler at a point spaced from said point of contact.

In testimony whereof I affix my signature.

EDWIN R. JEBOME.
